Inventor
W.B. FAULKNER

Chas. Parker

Attorney

UNITED STATES PATENT OFFICE.

WILLIAM BALLARD FAULKNER, OF PARIS, KENTUCKY.

LOCK.

Application filed September 24, 1923. Serial No. 664,569.

To all whom it may concern:

Be it known that I, WILLIAM B. FAULKNER, a citizen of the United States, residing at Paris, in the county of Bourbon and State of Kentucky, have invented certain new and useful Improvements in Locks, of which the following is a specification.

This invention relates to locks, and more particularly to permutation locks.

10 An object of the invention is to provide a lock controlled by a pawl and a plurality of disks having notches, which notches must be arranged in alinement with each other to permit the pawl to be actuated to release the hasp of the lock.

A further object is to provide a padlock of this character in which the combination may be changed innumerable by rearranging the disks.

20 A further object of the invention is to provide a lock of this character which will be rendered inoperative if the pawl is maintained in engagement with the disks while the disks are being set, thus preventing the lock from being opened by "feeling".

In the accompanying drawings, I have shown one embodiment of the invention. In this showing:

Figure 1 is a front elevation,

30 Figure 2 is a central vertical sectional view,

Figure 3 is a transverse vertical sectional view on line 3—3 of Figure 2,

Figure 4 is a horizontal sectional view on line 4—4 of Figure 2,

Figure 5 is a detail sectional view on line 5—5 of Figure 2,

Figure 6 is a detail unassembled view of the rotating disks,

40 Figure 7 is a perspective view of the hasp and pawl, and,

Figure 8 is a perspective view of a spring washer arranged on top of the disks.

Referring to the drawings, the reference 45 numeral 1 designates generally the casing of the lock which is formed in two sections to secure them to each other in any suitable manner. A top plate 2 is carried by one section of the casing. This plate is provided with openings adjacent each side for the passage of a shackle 3. One arm of the shackle terminates immediately within the casing and the other arm is extended down-

wardly, as indicated at 4. The other section of the casing is provided with a plate 5, 55 adapted to be arranged beneath the top plate and limit the inward movement of the shackle.

A pin 6 is secured to the inside of the casing and extends transversely thereof. 60 This pin is adapted to receive the rotating disks by means of which the locking pawl is controlled.

The operating mechanism consists of a lower disk 7 arranged on the pin 6, and provided with a ring gear 8 at its periphery. This disk is provided with a plurality of concentric openings 9, arranged adjacent the center. These openings are threaded for the reception of a screw 10. A disk 11 is arranged over the bottom disk or gear 7 and this disk is provided with a plurality of openings 12 concentrically arranged adjacent the center, one of which is adapted to receive the screw 10. The openings 12 are spaced from each other a greater distance than the openings 9. The disk 11 is provided with a notch 13 in its periphery and is further provided with a plurality of notches 14, smaller in size than the notch 13. An upstanding pin 15 is mounted on the upper face of the disk. A plurality of disks 16 are arranged over the disk 11 and these disks are provided with arcuate slots 17 for the reception of the pin 15. As shown, the slots vary in size, the slot in the lower disk being smaller than the slot in the next adjacent disk, and the slot in the top disk being longer. The disks are separated from each other by means of washers 18 which washers are provided with arms 19 having openings 20 therein. These openings are adapted to receive pins 21 carried by the casing, which prevent rotation of the washers and thus prevent rotation of the disks by friction. Each of the disks 16 is provided with a notch 22 adapted to be alined with the notch 13 in the bottom disk when the lock is to be opened.

The disks are revolved by means of a 100 knob or handle 23 arranged on the bottom of the lock casing and extending through the casing. The inner end of this member is supported in a plate 24 and is provided with a pinion 25 meshing with the ring gear 8. 105

The arm 4 of the shackle is provided with a recess 26. A pawl 27 is pivotally mounted on a pin 28 within the casing and the upper end of this pawl is provided with a tooth 29 arranged adjacent the disks and adapted to be received in the notches 13 and 22. The opposite side of the pawl is provided with a tooth 30 adapted to be received in the recess 26 of the shackle. The lower end of the pawl is provided with a toe 31 adapted to be received in a groove 32 of the rotatable operating member. It is further provided with a heel 33 arranged beneath the shackle and adapted to raise the shackle to the dotted line position shown in Figure 2 of the drawings, when the lock is released and the pawl swung on its pivot. The under face of the disk or gear 7 is provided with suitable indicia 34 and the casing is provided with an opening 35 through which the indicia may be read. The casing is shaped to form a pointer 36 to permit accuracy in reading the figures 34.

The upper washer 18 is provided with a resilient arm 37 extending over the body of the washer and having a central opening 38 for the reception of the pin 6. This arm 30 engages the opposite side of the casing when in position (see Figure 3) and forces the washers and disks into snug engagement with each other on the pin.

The operation of the device is as follows: The gear 8 is revolved in first one direction and then the other by means of the operating member, through the rotation of the knob 23. When the gear is revolved, the bottom disk 11 moves with it and the pin 15, passing through the slot 17, will move each of the other disks 16 when the pin engages the end wall of the slot. The combination is read through the opening 35 and the operating member revolved in opposite directions the proper number of times to arrange the notches 13 and 22 in alignment with the tooth 29. When this has been accomplished, an outward pull on the knob 23 swings the pawl on its pivot to the dotted line position shown in Figure 2 of the drawings, and the shackle is forced upwardly to lift the short arm of the shackle over the top of the casing. It will be apparent that if the disks are not properly set with the notches in alignment, the edges of the disks prevent the pawl from being swung on its pivot and the tooth 30 in engagement with the recess 26 prevents the shackle from being lifted. The tooth 29 of the pawl is provided with an extension 39 that will enter the notches 14 of the lower disk 11 if an attempt is made to move the pawl on its pivot before the disk is properly set, by pulling the knob 23 outwardly and locking the parts

against further movement. This prevents the combination from being set or released by "feeling."

The combination may be changed as desired by altering the position of the gear 7 and disk 11 with respect to each other. The screw 10 may be removed from the openings in which it is arranged and placed in different openings in these two members. In order to provide a wide range of combinations, the openings 9 and 12 are arranged at different distances from each other. The combination may also be changed by substituting disks 16 having slots 17 of different sizes.

It is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described my invention, I claim:

1. A padlock comprising a casing, a shackle mounted in said casing, a pivotally mounted pawl normally engaging said shackle to retain it in locked position, a gear mounted in said casing, a pin carried by said gear, a plurality of disks arranged concentrically with said gear, said disks being provided with arcuate slots for the reception of said pin and being further provided with notches adapted to be aligned with said pawl to permit said pawl to be swung on its pivot to release said shackle, and means for rotating said gear.

2. A padlock comprising a casing, a shackle mounted in said casing, a pivotally mounted pawl normally engaging said shackle to retain it in locked position, a gear mounted in said casing, a pin carried by said gear, a plurality of disks arranged concentrically with said gear, said disks being provided with arcuate slots for the reception of said pin and being further provided with notches adapted to be aligned with said pawl to permit said pawl to be swung on its pivot to release said shackle, and an operating member extending through said casing and connected to said gear to permit rotation of said gear.

3. A padlock comprising a casing, a shackle mounted in said casing, a pivotally mounted pawl normally engaging said shackle to retain it in locked position, and means for normally preventing movement of said pawl, said means comprising a plurality of disks, each of said disks being provided with a notch in its periphery adapted to be aligned with said pawl to permit said pawl to be swung on its pivot to release said shackle, an operating member extending through said casing and con-

nected to said disks to rotate them, said operating member being provided with a groove, and a toe formed on said pawl and received in said groove to permit operation of said pawl when said disks are alined.

4. A device constructed in accordance with claim 3 wherein said gear is provided with a plate having a plurality of peripheral notches smaller in size than the notches in said disks, and said pawl is provided with an extension adapted to enter one of

said notches if said pawl is moved toward said disks during the rotation of said disks whereby further rotation of said disks is prevented.

15

In testimony whereof, I affix my signature in presence of two witnesses.

WILLIAM BALLARD FAULKNER.
